VACUUM TONSILLECTOME

Edward S. Ryan, Sheboygan, Wis.

Application July 5, 1932. Serial No. 620,762

8 Claims. (Cl. 128—309)

The invention relates to improvements in vacuum tonsillectomes and more particularly to an improved structure and adjustable mounting for the tonsil receiving cup.

5 An object of the invention is to provide an effective device to facilitate a thorough enucleation of a patient's tonsil with the capsule intact, without unnecessary injury to or excessive bleeding by the patient.

10 Another object is to provide an improved instrument of the character described which is well balanced and easy to manipulate, thus giving a maximum efficiency, and readily adjusted to different positions to the convenience of the operator, permitting use of one hand leaving the other hand free.

15 Another object is to provide a sliding and pivotal mounting for the tonsil receiving cup whereby said cup may be adjusted relative to the loop or snare associated therewith and improved means to adjust the position of said cup and retain it adjusted.

The foregoing and such other objects of the invention as will appear hereinafter as the description proceeds will be more readily understood from a perusal of the following specification, reference being had to the accompanying drawing, in which:

20 Fig. 1 is a side elevational view of the improved vacuum tonsillectome.

Fig. 2 is an enlarged longitudinal sectional view of the tonsillectome.

25 Fig. 3 is a vertical transverse sectional view taken on line 3—3 of Fig. 2.

30 The instrument described is adapted for use to remove tonsils, the operation being made extremely simple and safe in that almost no blood is lost by the patient and the enucleation thereof is quickly accomplished and thorough. As shown in the accompanying drawing, the improved instrument preferably embodies a sleeve 11, preferably substantially square in cross section, of the known type having a finger ring or grip 12 at one end and suitable means (not shown) at its other end to receive detachably one end of a cannula 13. Slidable within the cannula is a stem 14, preferably of heavy wire, having a fine wire loop or snare 15 at one end extending normally beyond the free end of the cannula. The other end of the wire 14 is attached to a collar 16 slidable on sleeve 11, said collar having finger rings or grips 17 adapted to be engaged to move the collar toward the grip 12 on the sleeve 11 and draw the snare 15 into the cannula 13 for a purpose to be described later.

A bracket 18 consisting of a square tubular body 19 and spaced longitudinal flanges 21 is slidably mounted on cannula 13.

40 A tonsil receiving cup 22, including a tubular stem 23, has spaced ears 24 thereon pivotally connected with flanges 21 by a pin 25 whereby said cup may be moved toward and away from the plane of the snare as shown in full and dotted lines in Fig. 2. Pivotal and longitudinal adjustment of said cup relative to the snare is necessary to facilitate working of the tonsil to be removed into the cup.

45 In operation the snare 15 is slipped about the tonsil and the tonsil is then worked into the cup with the fingers of one hand, the operator holding the instrument with the other hand by means of loops 12 and 17. While the tonsil is being pressed into the cup said cup is moved, in a manner to be described, toward the snare until the cup completely embraces the tonsil leaving only 50 the base exposed. The finger grips are then squeezed to move the collar 16 toward the loop 12 and the snare, upon being drawn into the cannula, completely enucleates the tonsil. As it is desirable to collect the blood and secretions in 55 the cup 22 it is necessary to produce a rarefaction of air therein and to this end the stem 23 of the cup is connected with a suitable vacuum pump (not shown) by a flexible tube 26.

60 Adjustment of the cup relative to the plane of the snare preferably is accomplished by manipulation of means operable by the same hand holding the instrument. This is desirable since such a structure leaves the other hand free to press and hold the tonsil in the cup while said cup is 65 being moved into position and during enucleation. As shown the ears 24 on the stem 23 preferably extend rearwardly of the bearing pin 25 and carry therein a rotatable pin 27 having a trigger, comprising parts 28—29, fixed thereon. The part 70 28 of said trigger is arcuate and has teeth 31 adapted to cooperate with serrations 32 on the body 19 of sleeve 18 and the other trigger portion 29 provides a finger piece which extends to within reach of the hand holding the instrument. A spring 33 normally holds the teeth 31 75 in engagement with the serrations 32 and upon disengagement thereof the cup may be adjusted about its pivot and then by releasing the trigger locked in adjusted position.

80 It is apparent from the foregoing that the adjustment and operation of the improved tonsillectome is accomplished by the same hand holding the instrument, thus leaving the other hand free to press the tonsil into the cup. The result 85

obtainable with this structure, as reflected in the work accomplished thereby, is far superior to that obtained with other known devices since complete insertion of the tonsil into the cup is readily accomplished, and clean enucleation is possible. With prior devices, because of the difficulty encountered in working the entire tonsil into the cup, fragments of the tonsil very often remain necessitating, for their removal, further operation with a knife, with increased injury and discomfort to as well as loss of blood by the patient.

Although an exemplary embodiment of the improved tonsillectome is disclosed in the accompanying drawing and described in detail herein, it is to be understood that the instrument may embody such modifications and variations as will fall within the spirit of the invention and the scope of the appended claims.

20 I claim:

1. A surgical instrument including finger grips one of which carries a sleeve having a cannula extending therefrom and the other being operatively connected with one end of a stem reciprocably mounted in said cannula, a loop on the free end of said stem extending beyond the free end of said cannula, a bracket slideable on said cannula, a tonsil receiving cup pivotally mounted on said bracket for adjustment at right angles to the plane of said loop, and means to hold said cup in adjusted position.

2. A tonsillectome including a cannula having a stem reciprocably mounted therein, a snare on one end of said stem normally extending beyond the end of said cannula, a tonsil receiving cup, mounting means for said cup whereby the plane of its open end may be moved toward or away from the plane of said snare, and means to retain said cup in adjusted position.

3. In a tonsillectome including a stem reciprocable in a cannula having a snare on one end, a tonsil receiving cup having its open end disposed in the plane parallel to the plane of said snare, a stem on said cup, said stem having ears pivotally connected to a bracket on said cannula whereby the distance between said planes may be varied, and means on said ears co-operating with said bracket to retain said cup adjusted.

4. In a tonsillectome including a cannula having a reciprocable stem therein, a finger grip on one end of said stem and a snare on the other end normally extending beyond one end of said cannula, a tonsil receiving cup having a tubular

stem pivotally mounted on a bracket on said cannula, the plane of the open end of said cup being parallel with the plane of said snare, and a latch on said tubular stem co-operating with means on the bracket to retain said cup adjusted relative to said snare.

5. A tonsillectome including a bracket and a cannula, the latter having a reciprocable stem therein, a snare on one end of said stem normally extending beyond one end of said cannula, a tonsil receiving cup including a tubular stem pivotally mounted on said bracket, the open end of said cup being in axial alignment with said snare and having the plane of its open end substantially parallel with the plane of said snare, a latch on said tubular stem having a segment at one end, and means on said bracket adapted for engagement by said segment to hold the cup adjusted relative to said snare.

6. A tonsillectome including a cannula having a reciprocable stem formed with a snare on one end, a tonsil receiving cup including a stem pivotally mounted on a bracket carried on said cannula for adjustment relative to the plane of said snare, and a trigger on said tubular stem arranged for co-operation with means on said bracket to facilitate adjustment of and lock said cup in adjusted position.

7. A tonsillectome including a cannula mounted at one end in a sleeve having a finger grip thereon, a stem in said cannula having a snare on one end and connected at its other end with means on the sleeve to draw said snare into the cannula, a bracket adjustable on said cannula, a tonsil receiving cup including a tubular stem mounted on said bracket for adjustment toward and away from the plane of the snare, and means on said tubular stem co-operating with means on said bracket to facilitate adjustment of and lock said cup in adjusted position.

8. A surgical instrument including a cannula having a reciprocable stem therein and a snare on one end of said stem extending beyond the end of said cannula, means to draw said snare into said cannula, a bracket on said cannula, a tonsil receiving cup including a tubular stem, said tubular stem being pivotally mounted on said bracket for adjustment of the cup toward and away from the plane of said snare, and a trigger carried by said stem adapted to co-operate with means on the bracket to hold said cup in adjusted position.
